UNITED STATES PATENT OFFICE.

HALSTEAD T. HOOKER, OF MARYVILLE, MISSOURI.

SAFETY NECK-YOKE.

No. 848,826.

Specification of Letters Patent.

Patented April 2, 1907.

Application filed August 6, 1906. Serial No. 329,462.

To all whom it may concern:

Be it known that I, HALSTEAD T. HOOKER, a citizen of the United States, residing at Maryville, in the county of Nodaway and State of Missouri, have invented a new, useful, and Improved Safety Neck-Yoke, of which the following is a description, reference being had to the accompanying drawings, forming a part of this specification, in which corresponding letters of reference in the different figures indicate like parts.

The object of my invention is to provide a device which may be used either as a neck-yoke for supporting the tongues of vehicles or as a safety attachment to be used in connection therewith, said device being made light and simple and so constructed that it may, in effect, form a part of the harness.

To these ends my invention consists in the combination of elements hereinafter more particularly described, and definitely pointed out in the claims.

In the drawings, Figure 1 is a perspective view of my improved safety appliance as it would appear when connected with a pole of a vehicle; and Fig. 2 is a side view of a portion of a vehicle-pole, showing the yoke portion of said device connected therewith, one of the arms thereof being removed to more clearly display the strap connection.

Referring to the drawings, *a* represents generally a metal yoke, preferably cast in steel or malleable iron or stamped from heavy sheet metal. Said device is provided with a ring portion *b*, having an opening therein adapted to receive the end of an ordinary vehicle-pole *c*. Integral with the ring *b* and branching in opposite directions therefrom are upwardly-bent arms *d* *d*, each having a loop *e* upon its upper end for the reception of a strap *f*. Each of the straps *f* is provided with a buckle *g* for adjusting its length and a snap-hook *h* for connecting the same with a ring or staple upon the hame or other part of the harness.

Integrally formed upon or otherwise attached to the top portion of the ring *b* is a rearwardly-extended arm or loop *i*, having an elongated opening *j* therein for the reception of a guard-strap *k*, which is provided with

a buckle or other suitable fastening device *l*. The loop-arm *i* is arranged to extend above and preferably parallel with the pole *c*, which is provided with the usual stop *m* upon the under side.

In attaching the device the strap *k* is unbuckled and the pole is projected through the ring until the latter rests against the stop *m*. The strap *k* is then buckled around the pole in the manner shown behind the stop. This feature is of primary importance as a factor of safety. Not only is it desirable to provide means to enable the team to hold back the load in case of the breaking of the ordinary neck-yoke, but it is also equally desirable to prevent the tongue from becoming disconnected in case a tug should break or become unhitched. The latter is frequently a source of serious accident. With my improved device the team is not only enabled to hold back the load, but by reason of the arm *i* and strap *k*, which latter is connected to the pole behind the stop *m*, the breaking of a tug will not permit the pole to be released.

It is obvious that an ordinary neck-yoke may be attached to the pole immediately in front of the ring *b*; but, as stated, the device may be used without it. In either event it is only necessary to buckle or unbuckle the strap *k* in connecting the device to or disconnecting it from a vehicle, it being unnecessary to detach it from the harness.

Having thus described my invention, I claim—

1. A safety device for supporting vehicle-poles, consisting of a transverse yoke having a ring for the reception of the end of the pole in front of the pole-stop, means for connecting the respective ends thereof with the harness, a short rearwardly-extended arm connected with said ring above the pole and a strap attached to said arm, said strap being provided with a detachable fastening device and arranged to encircle the pole immediately behind and in contact with the pole-stop, whereby said stop may be caused to engage the ring upon one side and the strap upon the other.

2. A safety device of the class described, comprising a yoke formed in one piece with

loops at the respective ends, an intermediate pole - ring, a short integral rearwardly-extended arm, a loop therein for the reception of a strap and a strap therein provided with a buckle, said loop being parallel with the axis of the pole to enable the strap to encircle the latter.

In testimony whereof I have signed this specification, in the presence of two subscribing witnesses, this 1st day of August, 1906.

HALSTEAD T. HOOKER.
